UNITED STATES PATENT OFFICE.

FRANK PFAHL, OF NEW YORK, N. Y.

DESIGN FOR A BOTTLE.

SPECIFICATION forming part of Design No. 16,549, dated February 23, 1886.

Application filed January 13, 1886. Serial No. 188,115. Term of patent 13 years.

To all whom it may concern:

Be it known that I, FRANK PFAHL, a citizen of the United States, residing at New York, in the county and State of New York, have invented and produced a new and original Design for Bottles, of which the following is a specification, reference being had to the accompanying drawing, forming part thereof.

My invention consists in making the walls and neck of the bottle conform as near as may be in outline to the configuration of a street lamp and supporting post provided with a base-plate.

The accompanying drawing shows a side elevation of my newly-designed bottle. The body A of the bottle, together with the neck B, is made to conform to the outline or configura-

tion of a street lamp and supporting-post, there being added the laterally-extended arms C C below the portion representing the lamp-globe, the base D of the body of the bottle, representing the lamp-post, being spread out to form a suitable base.

I claim—

The herein-described design for a bottle for containing fluids, in which the body of the bottle, together with its neck, is made to conform to the general outline of a street lamp and supporting post, terminating at its lower end in a laterally-extending base, as shown.

FRANK PFAHL.
